FRIEDRICH EHRMANN, OF FEUERBACH, STUTTGART, GERMANY, ASSIGNOR TO ROBERT BOSCH AKTIENGESELLSCHAFT, OF STUTTGART, GERMANY

PROCESS OF FORMING COMPOUND METAL BODIES

Application filed February 11, 1927, Serial No. 167,564, and in Germany April 19, 1926.

This invention relates generally to processes of forming compound metal bodies and it relates more particularly to processes of applying an outer or inner jacket to pressed metal rods, tubes, etc. For this purpose it has been proposed to place a rod made of the core metal, inserted into a completely formed tube made of the covering metal, into a cold press and to draw both together through the mouthpiece of the press. In doing so the covering tube is pressed firmly upon the core rod and moreover both are constricted and stretched proportionately in accordance with the opening in the mouthpiece of the press.

This known process is nevertheless difficult and expensive. That is, the core rod and the covering tube must be passed one or more times through other accurately working presses in order that they may be suited for the known process. This process is suited, moreover, only for relatively soft easily workable metals.

According to the present process, which is an essentially simpler and cheaper process than that just described and which is adapted to most metals, the metal of the core and the metal of the jacket, roughly preformed in raw state, are superposed in proper order in the receiver of the press. If these raw pre-formed blocks are exposed to the pressure of the press the jacket metal is carried along upon the rod of the core metal as an entirely uniform firmly clinging coating.

In the drawings is shown an example of the press intended for carrying out the process, represented in working position.

Fig. 1 shows in section a press for applying an outer coating.

Fig. 2 also in section, shows a press for the inner coating of tubes.

In each case there is a cylinder *a*, which is intended for the reception of the metal block to be pressed out, the cylinder on one end being closed off by a plate *b* having a thick wall. In the plate *b* is a hardened matrix or die *c*, the hole *d* of which corresponds to the cross section which the rod to be pressed is to have. In the other end of the cylinder *a* is a plunger *f* which under sufficient pressure forces the metal charge

of the cylinder *a* out through the mouthpiece *c* in the form of a rod.

In the example shown in Fig. 1 a block *A* of metal for the core of the rod to be pressed is placed in the cylinder *a* in accordance with the process. The block is conically pointed at the end turned towards the mouthpiece *c* and thereby leaves space for the conical ring *B* of the metal which is to form the coating for the rod.

With sufficient pressure of the plunger *f* the block *A* placed in position and at press temperature is forced through the mouthpiece and emerges from it as a rod. At the same time a certain portion of the metal ring *B* is carried along by the core metal flowing towards the mouthpiece and this remains clinging to the rod of the metal core originating in *A* as an entirely uniform closely adhering coating. The coating clings as firmly as though it were welded to the core metal and it is completely uniform over the whole length of the rod up to 30 m. and more.

As can be seen the blocks do not need to fit each other very closely, as in the known processes, for they are not placed one within the other but rather are placed one behind the other in layers. Those pieces which as female and male cones are placed one within the other need to fit each other only roughly and with much less exactitude than is necessary for very simple, cheap pieces hammered on an anvil.

In the example shown in Fig. 2 the press plunger *f* is longitudinally bored through and in known manner receives the fixed mandrel *g* which is necessary for making tubes. In this case the block *C* of the metal forming the tube has a conical depression on the end remote from the mouthpiece *c*. Into this projects the conically pointed end of an annulus *D* made of the metal for the inner covering.

The block *C* in the pressing is forced out as a tube between the mandrel *g* and the wall of the mouthpiece *c*. In this operation the annular block *D* is carried along and brought out by the tube produced, in the form of a tightly clinging inner coating.

The thickness of the coating can be regulated by suitable changes in the size and shape of the rings B and D. For example, in the process according to Fig. 1 the flat rings of small cross section give thin coverings, thick rings with large cross section of sharp conical form on the contrary give thick-walled coverings.

The process is not limited to round cross sections or sections of similar form, but it can be used successfully upon cross sections of extended forms, for example, rectangles. Even in these cases there is produced an entirely uniform coating, the thickness of which upon the long sides of the rectangle is not different from that upon the short sides.

In the formation of rods, it will be seen from Fig. 1 that the pressure is applied directly on ingot or block A, the pressure being transmitted to the coating metal B, which metal is carried along through the die c by frictional engagement with the mandrel, as the latter is forced through the die. This feature further distinguishes the present invention from the prior processes.

In Fig. 2, instead of applying the pressure directly on the blank C (corresponding to A in Fig. 1) the pressure is applied directly to member D, corresponding to the ring B of Fig. 1, the pressure being transmitted to C.

Having described the invention, what is claimed is:

1. A process of forming compound metal bodies composed of a plurality of layers of metal which comprises placing the pieces of metal which are to form the compound body in a press provided with a restricted opening through which the metal is to be extruded, the adjacent ends of said pieces of metal being inclined toward said opening and simultaneously extruding said pieces of metal through said opening.

2. A process of forming compound metal bodies by pressing which comprises placing blocks of metal which are to form the completed body in a press, one of said blocks having a substantially central opening in the line of the pressing force, said block being placed adjacent a die, the other block of metal having a pointed end engaging in said opening, and extruding said blocks of metal simultaneously through the opening in the die by applying pressure directly to the pointed-end block only.

3. A process of forming compound metal bodies which comprises extruding a body of metal through a restricted opening and through a body of coating metal arranged adjacent said opening only whereby the first metal carries a layer of coating metal with it through said opening, the exterior surfaces of said first metal and the interior surfaces of the coating metal adjacent said opening being inclined toward the latter.

4. The process of forming compound metal bodies by extrusion through a restricted aperture which comprises forcing a body of metal through an opening in a second body of metal placed between the first metal and said aperture, whereby the second body of metal will be carried through said restricted aperture by the first metal as a coating thereon, the opening in said second body of metal tapering toward the restricted aperture, the pressing force being applied directly to the first metal only.

5. A process of forming compound metal bodies composed of a plurality of layers of metal which comprises placing in a press formed with a restricted opening, a block of metal having an opening therein larger than and tapering toward the press opening and another block of metal having a tapering end extending into the opening in the first block and extruding said blocks of metal simultaneously through said press opening.

6. A process of forming compound metal bodies composed of a plurality of layers of metal which comprises placing in a press with a restricted opening, a ring of metal having a conical interior with its small end toward said opening and a block of metal having a conical end extending into the interior of said ring and extruding said metals simultaneously through said opening.

7. A process of forming compound metal bodies composed of a plurality of layers of metal which comprises placing in a press formed with a restricted opening blocks of metal having complementarily formed surfaces inclined towards such opening and applying pressure directly to one of said blocks only to extrude simultaneously both blocks through said opening.

8. A process of forming compound metal bodies by extrusion through a restricted opening comprising forcing a body of metal over a substantially stationary body of coating metal and then through a restricted opening whereby said first metal engages the surface of the second metal and carries a layer of the latter with it through said opening.

9. A process of forming compound metal bodies which comprises forcing a body of metal through a body of coating metal and then through a restricted opening whereby said first metal carries a layer of coating metal with it through said opening.

10. A process of forming compound metal tubes composed of a plurality of concentric layers of metal which comprises placing in a press with a restricted opening and a mandrel passing centrally through said opening, a hollow block of metal having a tapered interior with its small end towards said opening and another hollow block of another metal having a tapered end extending into the interior of the first block and extruding

said metals simultaneously through said opening.

11. A process as in claim 10 in which the aperture in the first block at the point adjacent said opening is of smaller diameter than said opening.

12. A process as in claim 10 in which the taper of the conical interior of the first block is comparatively slight.

13. A process as in claim 10 in which pressure is applied directly to the second block only, whereby the conical end of the latter is forcibly driven into the space between the mandrel and the conical interior of the first block and then the metal of both blocks is extruded simultaneously through the press opening.

In testimony whereof I hereunto affix my signature.
